[57] CLAIM

The ornamental design for a modular planter trough, as shown and described.

DESCRIPTION

FIG. 1 is a perspective view of a modular planter trough showing my new design;

FIG. 2 is a reduced top view thereof;

FIG. 3 is a reduced bottom view thereof;

FIG. 4 is a reduced view thereof, both ends being identical;

FIG. 5 is a reduced side view thereof, both sides being identical.

The roughened surface shading on the four horizontal ribs is understood to repeat across the entirety of the ribs and to represent a contrasting surface treatment.
